(57) **CLAIM**

The ornamental design for a footwear lace tightening reel stabilizer, as shown and described.

DESCRIPTION

FIG. 1 is a front view of a footwear lace tightening reel stabilizer, showing my new design;

FIG. 2 is a left side view thereof;

FIG. 3 is a right side view thereof;

FIG. 4 is a top view thereof;

FIG. 5 is a bottom view thereof; and,

FIG. 6 is a perspective view thereof, as applied to a piece of footwear shown in broken lines in a used condition.

The broken lines shown in the drawings represent portions of the footwear lace tightening reel stabilizer that form no part of the claimed design.
